Primary Examiner — Bridget L Eland(74) *Attorney, Agent, or Firm* — NSIP Law**CLAIM**

The ornamental design for a mobile phone, as shown and described.

DESCRIPTION

FIG. 1 is a perspective view of a mobile phone;
 FIG. 2 is a front view of the mobile phone of FIG. 1;
 FIG. 3 is a rear view of the mobile phone of FIG. 1;
 FIG. 4 is a left-side view of the mobile phone of FIG. 1;
 FIG. 5 is a right-side view of the mobile phone of FIG. 1;
 FIG. 6 is a top plan view of the mobile phone of FIG. 1;
 FIG. 7 is a bottom plan view of the mobile phone of FIG. 1;
 FIG. 8 is a partial enlarged view of FIG. 4 that is included to more clearly depict the design feature on the front of the mobile phone, as viewed from the left-side view (a-a', b-b', c-c' d-d') of FIG. 4;

FIG. 9 is a partial enlarged view of FIG. 5 that is included to more clearly depict the design feature on the front of the mobile phone, as viewed from the right-side view (e-e', f-f', g-g', h-h') of FIG. 5; and,

FIG. 10 is a partial enlarged view of FIG. 7 that is included to more clearly depict the design feature on the front of the mobile phone, as viewed from the bottom plan view (1-1', 2-2', 3-3', 4-4') of FIG. 7.
